UNITED STATES PATENT OFFICE.

OVERTON WINSTON, OF MINNEAPOLIS, MINNESOTA.

HEADLIGHT.

1,276,605.

Specification of Letters Patent. Patented Aug. 20, 1918.

Application filed March 17, 1916, Serial No. 84,773. Renewed January 22, 1918. Serial No. 213,273.

To all whom it may concern:

Be it known that I, OVERTON WINSTON, a citizen of the United States, residing at Minneapolis, in the county of Hennepin and 5 State of Minnesota, have invented certain new and useful Improvements in Headlights; and I do hereby declare the following to be a full, clear, and exact description of the invention, such as will enable others 10 skilled in the art to which it appertains to make and use the same.

My present invention relates to electric headlights for automobiles and is in the nature of an improvement on, or modification 15 of mechanism disclosed and claimed in my co-pending application S. N. 74,341, filed January 26th, 1916, and entitled "Headlights". Particularly, the invention is directed to the improvement of means for 20 shifting the electric light bulb in respect to the reflector, whereby the bulb may be moved transversely toward and from the axis of the reflector. The bulb, however, is also preferably mounted for axial movements, or for movements on the axis of the 25 reflector, so as to bring the filament of the bulb to the focal center of the concave reflector.

The invention is illustrated in the accompany 30 drawings wherein like characters indicate like parts throughout the several views. Referring to the drawings:

Figure 1 is a vertical longitudinal section taken centrally through the reflector, some 35 parts being shown in full;

Fig. 2 is a detail chiefly on the same section as in Fig. 1, with some of the parts shown in full that are sectioned in Fig. 1, some parts also being broken away;

Fig. 3 is a front end elevation of the eccentric lamp holding sleeve and socket;

Fig. 4 is a rear end elevation of the same;

Fig. 5 is a vertical section showing the eccentric lamp holding sleeve and a portion 45 of the lamp socket in which it is mounted;

Fig. 6 is a transverse section taken on the line x^6 x^6 of Fig. 1; and Figs. 7 and 8 are diagrammatic views illustrating oscillatory movements of the lamp bulb.

The numeral 1 indicates the casing of an ordinary headlight, such as used on automobiles, and the numerals 2 and 3 indicate, respectively, the reflector and lens or glass plate of the headlight. The electric light bulb 4 illustrated is of the well known Edi-

swan single base type, but, of course, other types may be employed. As shown, however, this bulb has an outer contact sleeve 5 and an axial contact boss 6. The sleeve 5 is adapted to be telescoped into a lamp holding collar 7 that has an eccentric flange, by means of which it is swiveled in the front end of a lamp socket made up of a pair of telescoping cylindrical channels 8 and 9, the latter of which is mounted to slide within the former, but is held against rotation in respect thereto. The outer shell 8 of the lamp socket is provided with forwardly and upwardly projected lugs or arms that are connected by pivots 10 to a hollow bearing 60 head 11. This bearing head 11 is rigidly but detachably secured to the back of a reflector, by means of a flanged clamping nut 12 that has threaded engagement with an annular anchoring hub 13 rigidly secured to 65 the back of the reflector. The reflector 2 has an axial passage through which the front end of the lamp socket and the collar 7 are projected with clearance.

Swiveled in the rear end of the outer shell 80 8 of the lamp socket is an adjusting nut 14 that works on the threaded stem of a contact carrying head 15 mounted to slide within the outer shell 8 and provided with the customary forwardly spring-pressed contact 85 16 that engages the contact boss 6 of the light bulb. Here it may be stated that the electric connections to the lamp may be of the usual arrangement, provided for light bulbs of the character above stated.

In the construction illustrated, the lamp holding collar 7 has several longitudinal internal grooves 17, and on its inner end it is formed with small stop lugs 18 adjacent to said grooves and with long segmental channels 19 between said stops. The collar 5 of the light bulb, at its inner end, is provided with three lugs 20 adapted to be passed through the groove 17 and pressed inward and turned into engagement with 95 the long segmental grooves 19, and when engaged therewith, permitting rotary adjustments of the light bulb in respect to the collar 7. By rotary adjustments of the eccentric collar 7 in respect to the lamp socket 100 and by rotary adjustments of the bulb in respect to said sleeve, it is possible always to bring the filament of the bulb to a desired position even when it has been warped to one side of the axis of said bulb. This, how- 105 110

ever, is a feature more fully discussed in my prior application S. N. 64,661, filed of date, December 2, 1915, and entitled "Head-lights."

5 Rigidly secured on the body and rear end portion of the outer sleeve 8 of the lamp socket is a collar 21 preferably of soft iron or steel and adapted to serve as an armature, in coöperation with an upper and lower 10 electro-magnet 22 shown as secured to and supported by an annular ring 23 secured to the interior of the lamp housing 1 back of the reflector. This ring 23 is preferably of brass, aluminum or other non-magnetic 15 metal. The pole pieces 22^a of the magnets 22 are arranged for direct engagement with the cylindrical upper and lower surfaces of the armature collar 21, and they serve to limit the extreme movements of the said 20 armature, and hence, of the lamp socket and light bulb.

The rear end portion of the armature sleeve 21 is formed with upper and lower notches 24, the outer surfaces of which are 25 rounded so as to afford cam surfaces for a purpose which will presently appear. A small lock lever 25 is pivotally associated with each electro-magnet, being, as shown, intermediately pivoted to a lug 26 on the 30 pole piece thereof, with its outer end yieldingly pressed outward by a light spring 27, also shown as anchored to the said pole piece. The outer or free end portions of these lock 35 levers 25 are preferably of soft iron or steel, and so related to outer pole pieces 22^b of the magnets 22 that they act as armatures in coöperation therewith. At their inner ends, the said levers 25 are provided with wedge 40 acting lock heads 28 projected forward therefrom and having rounded or cam acting surfaces for engagement with the rounded or cam surfaces of the notches 24 in the armature sleeve 21.

Axial adjustments of the light bulb are 45 produced by rotary movements of the adjusting nut 14 and to this end, as shown, the said nut is provided, at its rear end, with radial grooves 30, adapted to be engaged by a rotary, axial movable so-called screw 50 driver 31 mounted in a suitable bearing 32 on the back of the casing 1. This adjusting device, however, is not a novel feature of the present application, but is disclosed and claimed in certain of my prior applications above identified.

The operation briefly described is as follows:

In the position of the lamp socket and bulb shown in Figs. 1 and 2, the filament of 55 the bulb is above the axis of the reflector, as required to throw the light beams onto the ground a short distance ahead of the machine; and in such position, the lamp socket is then locked by the head 28 of the upper lock lever 25 which is then wedged

between the radially diverging surface of the top of the armature sleeve 21 and the lower surface of the pole piece 22^a of the upper magnet. The upper spring 27 maintains this engagement and keeps the lower 70 surface of the armature sleeve 21 tightly pressed against the pole piece 22^a of the lower magnet. Thus, all possibility of rattling of the parts and vibration of the bulb in respect to the reflector is avoided. 75 When it is desired to raise the lamp socket and move the light bulb downward so that its filament will be at the axis of the reflector, as required when it is desired to project the light beam far ahead of the machine, it is only necessary to temporarily energize the upper electro-magnet. The first effect of this is to cause the pole piece 22^b of the upper electro-magnet to act upon the upper end of the upper lock lever 25 80 and thereby move its head 28 from between the pole piece 22^a and coöperating surface of the armature sleeve 21. The second effect of energizing the said upper magnet 22 is to cause the lower pole piece 22^a thereof, 85 to act upon the armature sleeve 21 and lift the rear portion of the lamp socket, thereby bringing the upper surface of the said sleeve into contact with the upper pole piece 22^b. When the upper magnet 22 is en- 90 ergized, the upper lock lever 25 will stand approximately in the position indicated by dotted lines in Fig. 1, and in such position, it will be noted, the rounded portion of its head stands slightly within the path of 100 movement of the outer extremity of the co-operating notch of the collar 21, so that the said parts will be engaged and will cushion the upward movement of the collar and rear end of the lamp socket. As the 105 said collar and lamp socket are moved upward under the action of the upper magnet, however, the head of the upper lever 25 will be forced into the upper notch of the collar 21 and will engage the same after the 110 fashion that the head of the lower lock lever is engaged with the lower notch in Fig. 1. In fact, the said upper and lower lock levers have like operations except that the actions of the said lock levers are reversed 115 in respect to the movements of the lamp socket.

With the construction described, axial movements of the section 9 of the lamp socket, and hence, of the lamp bulb, are 120 produced by rotation of the so-called nut 14 within the socket, and such adjustments serve to set the bulb filament at the focal center of the reflector. By offsetting the pivotal support of the lamp socket, to a 125 point above the axis thereof, important results are obtained. With the pivotal support for the lamp socket transversely intersecting the axis thereof, an upward movement, for instance, of the bulb, will cause 130

a rearward or backward movement of the lamp filament, in respect to the reflector. In most instances, this rearward movement is not desirable, but, on the contrary, to obtain the best results for short focus or short projection of the light beams onto the ground, the lamp bulb should be given a forward movement when moved upward, so as to advance the lamp filament, in respect

10 to the reflector. This result can be accomplished by offsetting the pivotal support of the lamp socket, as shown in the drawings.

In the diagram views, Fig. 8, the heavy dotted lines α indicate the horizontal axis 15 of the reflector, and the lamp bulb 4, which is diagrammatically indicated, is by full lines, shown as normally at the axis of the reflector, as required for long beam projection. The dotted lines at $4'$ indicate the 20 position of the bulb when the lamp socket is oscillated on the arc of a circle struck from the point b which is on the axis of the reflector, and the dotted line marked $4''$ indicates the position of the bulb when moved 25 upward on the arc of a circle struck from the pivot b' . The lamp at $4'$, it will be noted, is moved backward, while the lamp at $4''$ is moved forward, in respect to the normal position of the lamp. In the diagram view of Fig. 7, the dotted lines at $4'''$ indicate the raised position of the lamp when moved on the arc of a circle struck from the pivot b'' , which pivot is located above the axis α of the reflector, such a distance 35 half way between the upper and lower positions of the lamp bulb, so that the bulb, in extreme positions, is on a vertical line.

Attention is further called to the following facts: For illustration, we will assume 40 that the axis of the lamp holding collar 7 is offset one thirty-second of an inch from the axis of its eccentric flange. In this case, the lamp holding socket in which the said eccentric flange is swiveled, should be so arranged 45 that when in a horizontal position, its axis will be parallel with, but offset below the axis of the reflector one thirty-second of an inch, or the distance of eccentricity of the eccentric flange of said collar 50 7. With this arrangement, regardless of whether the lamp filament is at the true axis of the lamp, or whether it is warped to one side, the said filament may always be adjusted so that it will be at the axis of the 55 reflector when the socket is in a horizontal position.

The above described three-point interlocking connection between the bulb and socket is important. Usually one, and sometimes 60 2 lock lugs and coöperating grooves are employed, but neither of such arrangements provides the best means for connecting the lamp to the socket. It is a well known fact that three points determine the position of 65 a plane, and on this same principle, the en-

gagement of the three lugs with three corrugations or shoulder surfaces will determine the position of the axis of the light bulb in respect to the axis of the socket. It is, of course, assumed that there is sufficient play 70 between the shank of the bulb and the seat of the socket or holding collar to permit the above noted self-adjustment of the bulb in respect to the socket.

What I claim is:

1. In a headlight, the combination with a reflector and a lamp socket that is movable in respect to the axis thereof, of upper and lower magnets for moving said socket, and upper and lower locks for holding said 80 socket alternately in lowered and raised positions, the said locks having portions working with wedge-like actions between said socket and the pole pieces of the respective magnets.

2. In a headlight, the combination with a reflector and a lamp socket that is movable in respect to the axis thereof, of upper and lower magnets for moving said socket, and upper and lower locks for holding said 90 socket alternately in lowered and raised positions, the said locks having portions working with wedge-like actions between said socket and the pole pieces of the respective magnets, and armatures connected to said locks and subject to said magnets, whereby, when one of said magnets is energized, the coöperating lock will be released, the armature drawn toward the energized magnet, and the other lock rendered operative to set 95 said socket in such adjustment.

3. In a headlight, the combination with a reflector, of a lamp socket pivoted for movements which carry the lamp bulb toward and from the axis of said reflector, upper and lower electro-magnets having pole pieces operative upon and limiting the movements of said socket, and upper and lower lock levers having armatures subject to the respective upper and lower magnets 105 and having heads working between the coöperating pole pieces of said magnets and adjacent surfaces on said socket, the upper lever serving to lock said socket in a lowered position and the lower lever serving to lock 110 said socket in a raised position.

4. In a headlight, the combination with a reflector, of a lamp socket pivoted for movements which carry the lamp bulb toward and from the axis of said reflector, upper and lower electro-magnets having pole pieces operative upon and limiting the movements of said socket, upper and lower lock levers having armatures subject to the respective upper and lower magnets and 120 having heads working between the coöperating pole pieces of said magnets and adjacent surfaces on said socket, the upper lever serving to lock said socket in a lowered position and the lower lever serving to lock 125 130

said socket in a raised position, and the said socket having surfaces that engage the heads of said levers with cam-like actions and cushion the movements of said socket.

5. In a headlight, the combination with a reflector and a socket mounted for pivotal movements that carry the lamp bulb toward and from the axis of the reflector, of an electro-magnet operative on said socket to move 10 the same pivotally, and a lock device for locking said socket having also a cushioning action for stopping the movement thereof, the said magnet serving to release said lock and to yieldingly hold the same in a 15 position to gradually stop the movement of said socket.

6. In a headlight, the combination with a casing and a reflector therein, said reflector having an axial passage, of an annular anchoring hub secured to the back of said reflector around the axial passage thereof and reinforcing said reflector, a bearing head detachably secured to said hub, a lamp 20 socket pivotally associated with said hub and head and arranged to support a lamp bulb through the axial passage of said reflector, and means applied to said head for imparting oscillatory movements to said socket.

25 7. In a headlight, the combination with a casing and a reflector therein, said reflector having an axial passage, of an annular anchoring hub secured to the back of said reflector around the axial passage thereof and reinforcing said reflector, a bearing head 30 detachably secured to said hub, a lamp socket pivotally associated with said hub and head and arranged to support a lamp bulb through the axial passage of said reflector, a ring secured to the interior of said casing, and electro-magnets supported by 35 said ring and operative on said socket to oscillate the same.

8. The combination with a casing and a reflector therein, of a lamp socket associated with said reflector to carry a lamp bulb toward and from the axis thereof, a bearing ring secured to the interior of said casing back of said reflector, and electro-magnets 40 supported by said ring and operative on said socket to oscillate the same.

45 9. In a headlight, the combination with a reflector, of a lamp socket, a lamp holding collar having an eccentric swivel connection 50 to said socket, the axis of said socket normally being offset from the axis of said reflector a distance equal to the eccentricity of

the eccentric swivel connection between said collar and socket.

55 10. In a lamp socket, a holding collar having three circumferentially spaced internal longitudinally extended grooves, and a shoulder at the inner extremities of said grooves, in combination with an electric light bulb having three circumferentially spaced outstanding lock projections on its shank, said lock projections being insertible through the three internal grooves of said holding collar and into engagement with the three shoulder surfaces of said collar, whereby, the said bulb will be definitely positioned in respect to the axis of said collar by the three engaging lock projections with the said three engaging shoulders.

60 11. In a headlight, the combination with a reflector, of a lamp support and an electric light bulb held thereby within said reflector, said lamp support being mounted to freely swing in a vertical plane on a fulcrum located at the rear of said reflector 65 and vertically offset from the axis of said reflector and lamp support.

12. The combination with a lamp socket, of a light bulb having on its shank three lock lugs normally engaging three contacting points on said socket and determining the position of said bulb in respect to said socket.

70 13. The combination with a lamp socket having three entrance grooves and a lock shoulder at the extremities thereof, a light bulb having on its shank three outstanding lock lugs insertible through said grooves and engageable simultaneously with three points on said lock shoulder, and yielding means within said socket normally holding said three lock lugs engaged with three points on said shoulder.

75 14. In a headlight, the combination with a reflector and a lamp socket that is movable in respect to the axis thereof, of an electro-magnet associated with and arranged to move said socket, and a lock for holding said socket in one extreme position, said lock having a portion working with a wedge-like action between said socket and the pole piece of said magnet.

In testimony whereof I affix my signature in presence of two witnesses.

OVERTON WINSTON.
